UNITED STATES PATENT OFFICE.

JAMES TROTTER, OF CHICAGO, ILLINOIS.

MECHANICAL DRAFT-PRODUCING DEVICE FOR LOCOMOTIVE ENGINES.

Application filed January 26, 1925. Serial No. 4,975.

To all whom it may concern:

Be it known that I, JAMES TROTTER, a citizen of the United States, residing at Chicago, in the county of Cook and State 5 of Illinois, have invented certain new and useful Improvements in Mechanical Draft-Producing Devices for Locomotive Engines, of which the following is a specification.

It is well known that locomotive draft is 10 ordinarily produced by exhausting the steam from the cylinders through a nozzle and that the draft is obtained at an excessive expenditure of power, due to back pressure of the steam upon the cylinder pistons, also consuming an excessive amount of coal for 15 work performed, on account of the restricted opening of the nozzle, to get the required draft.

Various attempts have been made to increase 20 the efficiency of the locomotive by the provision of draft producing devices arranged within the smoke box, but these devices have proven to be inefficient for the reason that they are subjected to intense 25 heat which interferes with their operation and often renders such devices completely inoperative.

It is one of the objects of the present invention to provide a mechanical draft producing 30 device to be used in conjunction with the exhaust steam from the cylinders for creating a forced draft in a locomotive boiler and which device will be located exterior of the smoke box and in a position where it 35 will be out of the way and at the same time will be readily accessible.

It is another object of the present invention to divide the draft by providing a partition 40 in the smoke box to divide the latter into two compartments one of which compartments is adjacent the flue sheet. A second partition is also provided to divide the compartment which is adjacent the flue sheet into two compartments to separate the top 45 or upper battery of flues from the lower ones.

A mechanical draft producing device is placed on top of the boiler and has communication with the upper compartment to 50 create a draft through the upper battery of flues when in action, while a draft is produced through the lower battery of flues by the exhaust steam from the cylinders when in action, discharging through the 55 front compartment in the smoke box and into the smoke stack, and by the natural

draft of the locomotive when the engine is not in operation.

The mechanical device is arranged to operate when the engine is in action and preferably through the medium of a steam turbine supplied with steam from the steam pipe that leads to the steam valve of the cylinder and being under control of the engineer.

As the super heater units extend into the upper battery of flues there should be no draft through these flues when the engine is not in operation for the reason that if the flame of the fire is passed through these 70 flues at that time, the super heater units would be damaged and would burn up as there will be no steam in the super heater units at that time, to protect them.

With this invention there will be provided a mild and continuous draft on the fire while the engine is in operation, thereby preventing the drawing of the coked coal from the fire box through the flues to the atmosphere, with the result that there will be a large percentage of saving in fuel and at the same time the efficiency of the boiler will be greatly increased.

Furthermore by the employment of this invention it is possible to employ a very large nozzle in the engine for the exhaust steam, thereby eliminating the heretofore fierce draft which consumes a great amount of fuel, and with the further result that back pressure in the cylinders will be reduced, 90 resulting in an increase of horsepower of the engine enabling the handling of a much larger and greater tonnage train than heretofore.

To the attainment of these ends and the 95 accomplishment of other new and useful objects, the invention consists in the features of novelty in substantially the construction, combination and arrangement of the several parts, hereinafter more fully described and 100 claimed and shown in the accompanying drawing in which;

Figure 1, is a diagrammatic end elevation of the smoke box of a locomotive engine having an apparatus constructed in accordance 105 with the principles of this invention applied thereto.

Figure 2, is a view partly in vertical longitudinal section and partly in elevation of the smoke box of a locomotive engine showing 110 this invention applied thereto and with parts omitted.

Referring more particularly to the drawing the numeral 10 designates generally the front end of a locomotive engine having a stack 11, a flue sheet 12 through which the 5 upper bank 13 and the lower bank 14 of the flues open, and a smoke box designated generally by the reference numeral 15.

A spark arrester embodying a substantially horizontal partition 16, a screen 17 and 10 an upright partition 18 divides the smoke box into two compartments, the partition 18 being spaced from and extending in a direction transversely of the flues and arranged in advance of the ends of the flues.

15 A supplemental substantially horizontal partition 19 extends across the space between the partition 18 and the flue sheet to form a closed chamber with which the upper bank 13 of the flues communicate and the partition 20 separates the upper bank of flues 13 from the lower bank 14.

An exhaust nozzle 20 discharges through the portion of the smoke box with which the flues 14 have communication and also 25 through the partition 16 into the stack 11 to create a suction in the smoke box and through the flues 14; and screen 17, which latter forms a portion of the spark arrester.

Super-heater pipes 21 having communication 30 with a header 22 extend into each of the flues of the upper bank 13 and a pipe 23 leads from the header 22 to the steam chest. The flow of steam from the header 22 through the pipe 23 and to the steam chest 35 is controlled in the ordinary and well known manner (not shown) from the engine cab.

Arranged in any suitable or convenient position, preferably on top of the boiler is a mechanical suction creating device 24 such 40 as a fan or the like, the inlet side of the casing of which has communication as at 25 with the chamber 26 formed by the partitions 18—19 and the flue sheet and end of the boiler.

45 The exhaust outlet 27 of the fan casing preferably discharges into the atmosphere so that when the suction creating device is actuated, suction will be created through the upper bank 13 of the flues.

50 Any suitable means may be provided for actuating the suction creating device such as a turbine motor 28 adapted to be itself actuated by steam supplied thereto preferably from the steam pipe 23, through the 55 medium of a pipe 29.

As the circulation of steam through the pipe 23 is controlled by the engineer, it will be manifest that the flow of steam through the pipe 29 will also be controlled, with the 60 result that when the engine is stopped by

controlling the steam in the pipe 23, the mechanical draft producing device will also be controlled or stopped, thus shutting off or stopping the suction in the flues 13, thereby preventing injury to the super-heater pipes 65 which extend into the flues 13, as these pipes will at the time the steam is shut off, be practically empty of steam.

The mechanical draft producing device 70 operates to create suction only in the upper bank 13 of the flues, while the exhaust steam, when the engine is running, and the natural draft when the engine is idle, causes a draft through the lower bank 14 of the flues. 75

While the preferred form of the invention has been herein shown and described it is to be understood that various changes may be made in the details of construction and in the combination and arrangement of the several parts, within the scope of the 80 claims, without departing from the spirit of this invention.

What is claimed as new is:

1. A mechanical draft producing device 85 for locomotive engines embodying in combination, a chamber in the smoke box, said chamber being constantly out of communication with the interior of the smoke box but having communication with only some of the flues of the boiler, and a mechanical suction 90 creating device exterior of the smoke box and chamber and having communication with the chamber for creating suction only through those flues that have communication 95 with the said chamber, said device cooperating with the exhaust steam for creating a draft over the entire area of the fire box grate. 100

2. In combination with the smoke box of a 105 locomotive engine, a partition therein forming with the flue sheet a chamber with which only a portion of the flues communicate and being closed to the other flues, a suction creating device exterior of the smoke box and chamber, the inlet side of said suction 110 creating device having communication with the chamber to create a suction through those flues which have communication with the chamber, a steam header, a steam pipe leading therefrom, a pipe leading from the said steam pipe to the said suction creating device for conveying steam to the suction creating device for actuating it, and an exhaust nozzle discharging into the smoke box exterior 115 of the said chamber.

In testimony whereof I have signed my name to this specification, on this 22nd day of January, A. D. 1925.

JAMES TROTTER.
